CLAIM

I claim a fabric and plastic materials four sided warning sign, as shown and described.

DESCRIPTION

FIG. 1 is a front view of the fabric and plastic materials four sided warning sign showing my new design;

FIG. 2 is a side view thereof;

FIG. 3 is a top view thereof;

FIG. 4 is a bottom view thereof;

FIG. 5 is a perspective view thereof; and,

FIG. 6 is a perspective view thereof showing the design in an alternate position.
